COMBINED SHOPLIFTING-PROOF GARMENT HANGER AND SUPPORT THEREFOR

Nils Ingemar Schwalbe, 9 St. Eriksgatan,
112 39, Stockholm, Sweden

Filed Sept. 23, 1974, Ser. No. 508,467

Claims priority, application Sweden Mar. 25, 1974

Term of patent 14 years

Int. Cl. D6—04; D20—02

U.S. Cl. D6—191

FIG. 1 is a front elevational view of a combined shoplifting-proof garment hanger and support therefor showing my new design;

FIG. 2 is a side elevational view taken from right of FIG. 1.

What I claim is:

The ornamental design for a combined shoplifting-proof garment hanger and support therefor, as shown.
